INDEXING DEVICE

Albert Blain, Philadelphia, Pa., assignor to Radio Corporation of America, a corporation of Delaware

Application February 5, 1938, Serial No. 188,947

5 Claims. (Cl. 116—124.2)

This invention relates to indexing devices such, for example, as may be employed in radio or television apparatus for adjusting and for indicating the angular adjustment of a tuning control or other shaft.

An object of the invention is to provide an indexing mechanism capable of being rapidly and accurately adjusted.

Another object of the invention is to provide a simple and inexpensive indexing device and one without gears whereby "back lash" and other objectionable features of the prior art are substantially obviated.

Another object of the invention is to provide an improved dual-ratio driving mechanism capable of being adjusted with micrometer accuracy.

Other objects and advantages, together with certain details of construction, will be apparent and the invention itself will be best understood by reference to the following specification and to the accompanying drawing, wherein

Figure 1 is a front elevational view of an indexing device constructed in accordance with the principle of the invention, and

Figure 2 is a side elevation, partly in section, of the device of Fig. 1.

In the drawing, 1 designates the base of a radio chassis and 2 a U-shaped bracket supported on said base. Immovably supported on bracket 2 is an index plate 3 and a bushing 4 through which extends a rotatable tuning control or other driven shaft 5. Shaft 5 is provided with an extension 5a, upon which a driving shaft in the form of a sleeve 6 is mounted for rotation. The driving shaft or sleeve 6 has a driving element, exemplified by a knob 7 secured to its outer end, and intermediate its ends has a fixed hub 8 secured thereto as by set screws 9. Also secured on the hub 8 for rotation with the driving shaft 6 is a dial 10 and behind this dial is a second dial 11 which is supported for relative movement with respect to the first dial; that is to say, the second dial 11 may be moved in a manner later described about the fixed hub 8 on the rotatable sleeve or driving shaft 6. As will hereinafter more fully appear, the indicia of the scales on these relatively movable dials may be read in connection with a common reference point, the reference point being exemplified in Fig. 1 by a pointer 12 which may be located at any convenient point about the periphery of these discrete scale-bearing surfaces 10 and 11.

Behind the inner scale 11 is a cam 13 which is fixed on the hub 8 so that it rotates with the hub, the outermost dial 10, and the driving shaft

6 when the knob 7 is turned. As clearly shown in Fig. 1, the cam selected for purposes of illustration has a rise of substantially 360° and is provided with a stop 14 which extends radially outward at the terminals of the rise.

Secured directly to the driven or main shaft 5 in the space intermediate the cam 13 and the forward face of the fixed index plate 3 is an outwardly extending arm or plate 15 which may be bent forwardly and then outwardly, as shown at 15a, Fig. 2, to present its central peripheral portion 15b (Fig. 1) in a plane parallel to its main surface. An arcuate slot 15c is preferably provided in the bend of the plate 15.

Plate 15 serves as a support for an L-shape link 15 member 16 which is pivoted thereon at a point remote from the shaft 5 by a pivot 17 (Fig. 1) located in the elbow of the L. One of the arms 16a of the L-shape member 15 extends through the slot 15c and is provided with a terminal portion 16b which extends rearwardly above and adjacent the periphery of the immovable index plate 3. Part 16b of the L arm constitutes a retaining member for a ball 18 which is adapted to be selectively seated in any of a plurality of complementary detents 3a which are arranged in spaced relation on the periphery of the index plate 3. To provide a spring force for maintaining the ball in a selected detent, the ball retainer is provided with a loop portion 16c at 25 the radial end of the L-arm 16a.

The other arm of the pivoted L is designated 16d; it is provided at its outer extremity with a cam follower 19 which is adapted to be maintained against the edge of cam 13 by a spring 20 which is anchored at one end to the plate 15 and bowed about the pivot 17 so that its opposite end exerts a biasing force against the arm 16a which is transmitted through the L to the cam follower.

It is now apparent that the ball 18, when it is seated in a detent 3a, constitutes an axis of rotation for the L-shape link member 16. Thus, any force applied through the cam follower 19 to the arm 16d of the L and tending to raise or lower the said arm will be converted into a rotary force which will be applied to the plate 15 through the pivot 17 which connects the L to the plate. Since plate 15 is fixed on the main shaft 5, the rotary force applied to this plate by the rise and fall or "toggle movement" of the L will drive that shaft. The "toggle" in this case may be considered to comprise (1) that portion of plate 15 which extends from the axis of the driven shaft 5 to the pivot 17 and (2) that portion of the 55

L-shape link member 16 which extends from the ball 18 to the pivot 17.

The force required to produce the above described toggle movement of the L-shape member is applied thereto through the cam follower 19 as it follows the rise of the rotating cam 13.

In Fig. 1, the cam follower 19 is shown against that surface of the cam stop 14 whereat the rise of the cam (as measured from the axis of the driving shaft) is shortest. Therefore, when the cam 13 is moved in a clockwise direction, the cam follower 19, in following the rise of the cam, will urge the arm 16d of the L upwardly thereby pivoting the L in a counter-clockwise direction about the ball 18, which, being in a detent, serves as an axis or center of rotation of the L. Now, since the L is fixed to the plate 15 by the pivot 17, the above described counter-clockwise movement of the L about its center of rotation (i. e. ball 18) will cause the plate and hence the driven shaft 5 (to which plate 15 is fixed) to be driven in the same (clockwise) direction as the driving shaft 6 and the cam 13 thereon are being driven.

Obviously, the angular distance that the main shaft 5 will be driven when the cam 13 is rotated 360° (i. e. to that position whereat the cam stop 14 is to the left of the cam follower 19) is a function of the radial distance the cam follower 19 must travel in moving from one side of the cam stop to the other side, around the cam. If this distance or "rise" is small (as it is in the illustrated embodiment of the invention), then the "step-down" ratio between the driving and driven shafts will be relatively enormous, so that very minute changes in the angular position of the driven shaft will be readily apparent to the operator in observing that dial scale 10 which is fixed to the driving shaft 6.

Any force additional to that required to bring the cam stop 14 against the cam follower 19 will unseat the ball 18 (the spring action of its retainer permitting this) and drive the plate 15 and hence the driven shaft 5 as long as such force is positively applied. Thus, the driven shaft may be said to be "directly coupled" to the driving shaft as long as the cam follower 19 is in contact with one side or the other of the cam stop 14.

As previously pointed out, the inner or larger, dial 11 is mounted to permit of its being rotated with respect to the outer, smaller, dial 10. Such movement is imparted to the inner dial 11 by the cam follower 19 which extends through a slot 11a provided for the purpose in the said dial. This slot 11a is made somewhat larger than the cam follower 19 so that no movement is imparted to the dial 11 by the previously described "rise and fall" of the L arm 16d to which the cam follower is affixed.

There are thirty-six detents 3a in the index plate 3 of the illustrated embodiment of the invention and there is a mark individual to each detent on the main (rear) dial scale 11. Thus, the main scale indicia represent 10° increments indicative of the angular position (with respect to the pointer 12) of the main tuning shaft 5. The secondary (front) scale 10 may be calibrated in units and fractions of units of 10°. This front scale 10 is read with reference to the zero position of the main scale 11, and the main scale is read with reference to the pointer 12. Thus, the two scales when read together provide a reading in degrees and fractions of a degree of the

angular position of the driven shaft 5 with respect to the pointer 12.

While the invention has been described as embodied in an indexing mechanism for radio apparatus, the invention is not limited to such application as the disclosure in this respect is merely illustrative for purposes of explaining the inventive concept. The invention is therefore not to be limited except as required by the prior art and the spirit of the appended claims.

What is claimed is:

1. In a device of the class described, a rotatable shaft, a sleeve mounted for rotation on said shaft, a cam fixed on said sleeve, said cam having a rise thereon and a stop at the terminals of said rise, an arm fixed on said shaft, an L-shape link pivoted at its elbow to said arm at a point remote from the axis of said shaft, a cam follower on one arm of said L and adapted to follow the rise of said cam and to engage said stop, a ball and a ball retainer on the other arm of said L, a fixed index plate having detents thereon arranged in spaced circumferential relation with respect to the axis of said shaft, said detents being positioned in the path of said ball, said ball when in a detent constituting an axis of rotation for said L when the cam follower thereon is raised or lowered by means of the cam; rotation of said L about the said ball-axis serving to transmit torque through its pivot to the arm to which said L is affixed and thence to said shaft; and means for rotating said sleeve.

2. The invention as set forth in claim 1 wherein in a main scale is provided, said main scale being mounted about the axis of rotation of said shaft and adapted to be moved by the cam follower in discrete steps when the axis of rotation of the L is shifted from one detent to another by the force transferred to the cam follower through the cam stop when said stop is rotated in contact with the cam follower.

3. The invention as set forth in claim 1 wherein in a main scale and a secondary scale are provided, said main scale being mounted to be driven in discrete steps by movement of said cam follower, and said secondary scale being mounted on said sleeve for rotation therewith, a fixed pointer for said main scale and means on said main scale constituting a reference point for said secondary scale.

4. In a device of the class described, a driving shaft, a driven shaft, a cam on said driving shaft, a stop on said cam, means comprising a toggle connected to said driven shaft and having a cam follower thereon biased to follow said cam, and means for changing the direction of motion of said toggle when said cam follower is moved in contact with said cam stop, whereby to alter the driving ratio between said shafts.

5. In a device of the class described, a driving shaft, a driven shaft, a cam on said driving shaft, a stop on said cam, a plurality of toggle elements connected to said driven shaft and having a cam follower thereon biased to follow the cam surface of said cam, said cam stop, cam follower and certain of said toggle elements constituting a direct driving connection between said driving and driven shafts, said cam surface, said cam follower and the other of said toggle elements constituting an indirect driving connection between said shafts, and means for changing from indirect to direct driving relation when said cam follower is moved in contact with said cam stop.
